Container and Packaging. Black pp. 38-400 ribbed skirt hinged flip top dispensing cap with unprinted pressure sensitive liner. No date specified. <URL:https://www.containerandpackaging.com/products/21/flip-top-caps/L001BK>. (Year: 0).*

Primary Examiner — George D. Kirschbaum*Assistant Examiner* — Darcey E Gottschalk(57) **CLAIM**

The ornamental design for a bottle cap having an inner lid, as shown and described.

DESCRIPTION

FIG. 1 is a front, top perspective view of a bottle cap having an inner lid showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof;

FIG. 8 is a cross-sectional view taken along line **8-8** of FIG. 6;

FIG. 9 is a cross-sectional view thereof showing the inner lid is depressed to break a bottom membrane;

FIG. 10 is a front, bottom perspective view thereof, showing the bottom membrane is broken; and,

FIG. 11 is a front, top perspective view of the bottle cap having an inner lid showing a bottle cover is open.

The broken line portion of the figure drawings is included to show unclaimed subject matter only and forms no part of the claimed design.

1 Claim, 6 Drawing Sheets(56)
